(57) **CLAIM**

The ornamental design for a curtain with apertures, as shown and described.

DESCRIPTION

FIG. 1 is a perspective view of a curtain with apertures showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is another perspective view in the condition of use thereof;

FIG. 9 is another perspective view in the condition of use thereof; and,

FIG. 10 is a partially enlarged view thereof.

The broken lines in FIGS. 8 and 9 depict environment that forms no part of the claimed design.
